No. 36,724.

Patented January 5, 1904.

UNITED STATES PATENT OFFICE.

NATHAN B. LEVY, OF SCRANTON, PENNSYLVANIA.

DESIGN FOR A WATCH-CHARM.

SPECIFICATION forming part of Design No. 36,724, dated January 5, 1904.

Application filed October 26, 1903. Serial No. 178,649. Term of patent 7 years.

To all whom it may concern:

Be it known that I, NATHAN B. LEVY, a citizen of the United States, residing at Scranton, in the county of Lackawanna and State of Pennsylvania, have invented a new, original, and ornamental Design for a Watch-Charm, of which the following is a specification.

Figure 1 represents a front elevation of a charm, showing this new, original, and ornamental design. Fig. 2 is an edge view thereof.

I claim as my invention—

The ornamental design for a watch-charm as shown in the accompanying drawings.

In testimony that I claim the foregoing as my own I have hereto affixed my signature in the presence of two witnesses.

NATHAN B. LEVY.
